US00D918880S

(12) **United States Design Patent** (10) **Patent No.:** **US D918,880 S**
Shu (45) **Date of Patent:** **** May 11, 2021**

(54) **DISPLAY MOUNT**

(71) Applicant: **SHENZHEN MENGXIANGYUAN FITNESS DEVELOPMENT CO., LTD.**, Shenzhen (CN)

(72) Inventor: **Hua Shu**, Shenzhen (CN)

(73) Assignee: **SHENZHEN MENGXIANGYUAN FITNESS DEVELOPMENT CO., LTD.**, Shenzhen (CN)

(**) Term: **15 Years**

(21) Appl. No.: **29/745,108**

(22) Filed: **Aug. 4, 2020**

(51) LOC (13) Cl. **14-03**

(52) U.S. Cl.

USPC **D14/239**

(58) **Field of Classification Search**

USPC D14/239, 371, 372, 373, 374, 375, 376, D14/377, 447-452, 125, 127, 128, 129, D14/335-337, 341, 126; D8/355, 363, D8/373; D6/672, 682

Primary Examiner — Lauren D McVey

(57) **CLAIM**

The ornamental design for a display mount, as shown and described.

DESCRIPTION

FIG. 1 is a perspective view of a display mount showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the display mount that form no part of the claimed design.

1 Claim, 8 Drawing Sheets
